(57) **CLAIM**

The ornamental design for the fireplace frame, as shown and described.

DESCRIPTION

FIG. 1 is an isometric view of a first embodiment of the fireplace frame showing our new design.

FIG. 2 is a front elevational view of the first embodiment.

FIG. 3 is a rear elevational view of the first embodiment.

FIG. 4 is a right-side elevational view of the first embodiment. The left-side elevational view of the first embodiment is substantially the same as the right-side elevational view. FIG. 5 is a top plan view of the first embodiment.

FIG. 6 is a bottom plan view of the first embodiment.

FIG. 7 is an isometric view of a second embodiment of the fireplace frame showing our new design.

FIG. 8 is a front elevational view of the second embodiment.

FIG. 9 is a rear elevational view of the second embodiment.

FIG. 10 is a right-side elevational view of the second embodiment. The left-side elevational view of the second embodiment is substantially the same as the right-side elevational view.

FIG. 11 is a top plan view of the second embodiment; and, FIG. 12 is a bottom plan view of the second embodiment. Any broken lines in the drawings are for illustrative purposes only and form no part of the claimed design.

The broken lines showing of portions of the fireplace frame and the interior of a firebox are for illustrative purposes only and form no part of the claimed design.

1 Claim, 6 Drawing Sheets
